BARREL FOR AIR ATOMIZATION ELECTRO- STATIC DEPOSITION SPRAY GUN

Ronald J. Blackwell, Passaic, and Seymour Devick,
Teaneck, N.J., assignors to Selectrostatic Corporation,
Lodi, N.J., a corporation of New Jersey

Filed Feb. 17, 1964, Ser. No. 78,670

Term of patent 3½ years

(Cl. D62—2)

FIG. 1 is a perspective view of a barrel for air atomization electrostatic deposition spray gun showing our new design;

FIG. 2 is a side elevational view thereof;

FIG. 3 is a top plan view thereof;

FIG. 4 is a front elevational view thereof; and

FIG. 5 is a fragmentary cross-sectional view taken substantially along the line 5—5 of FIG. 4.

The portions of the spray gun in FIG. 1 which are shown in broken lines are for illustrative purposes only.

We claim:

The ornamental design for a barrel for air atomization electrostatic deposition spray gun, substantially as shown and described.
